(57) **CLAIM**

The ornamental design for a control panel as shown and described.

DESCRIPTION

FIG. 1 is a front view of a control panel showing our new design;

FIG. 2 is a rear view of the control panel;

FIG. 3 is a top plan view of the control panel;

FIG. 4 is a bottom view of the control panel;

FIG. 5 is a right side view of the control panel; and,

FIG. 6 is a left side view of the control panel.

The broken lines showing portions of the article in the drawings form no part of the claimed design. The long dash, short dash broken lines indicate the boundaries of the claimed design and form no part of the claimed design.

1 Claim, 6 Drawing Sheets
